(57) **CLAIM**

The ornamental design for a solar-powered outdoor light, as shown and described.

DESCRIPTION

FIG. 1 is a perspective view of a solar-powered outdoor light embodying my new design.

FIG. 2 is a left side elevational view thereof on a reduced scale, the right side elevational view being a mirror image thereof.

FIG. 3 is a front side elevational view thereof on a reduced scale, the rear side elevational view being a mirror image thereof.

FIG. 4 is a bottom plan view thereof on a reduced scale; and,

FIG. 5 is a top plan view thereof on a reduced scale. The broken lines shown in the drawing form no part of the claimed design.
